[57] **CLAIM**

The ornamental design for a bottle, as shown and described.

DESCRIPTION

FIG. 1 is a front elevational view of a bottle showing my new design, the rear elevational view being a mirror image thereof;

FIG. 2 is a side elevational view thereof, the other side being a mirror image thereof;

FIG. 3 is a bottom plan view thereof;

FIG. 4 is a top plan view thereof;

FIG. 5 is a front elevational view of a bottle showing a further embodiment of my new design, the rear elevational view being a mirror image thereof;

FIG. 6 is a side elevational view thereof, the other side being a mirror image thereof;

FIG. 7 is a bottom plan view thereof; and,

FIG. 8 is a top plan view thereof.

The broken line showing of an upper portion of the bottle in FIGS. 5, 6, and 8 is for illustrative purposes only and forms no part of the claimed design.
